UNITED STATES PATENT OFFICE.

WILLIAM J. PARKINSON, OF ROCHESTER, NEW YORK, ASSIGNOR TO PRITCHARD-STAMPING COMPANY, OF ROCHESTER, NEW YORK, A CORPORATION OF NEW YORK.

GUARD FOR MACHINERY.

1,084,897.

Specification of Letters Patent. Patented Jan. 20, 1914.

Application filed September 18, 1912. Serial No. 721,082.

To all whom it may concern:

Be it known that I, WILLIAM J. PARKINSON, a citizen of the United States, and resident of Rochester, in the county of Monroe and State of New York, have invented certain new and useful Improvements in Guards for Machinery, of which the following is a specification.

This invention relates to guards, such as are employed in connection with presses and other machines, to prevent injury to the hand of an operator through accidental contact with the operating-instrumentalities or moving parts of such machines. In guards of the kind in question, especially as used in connection with presses, it has been common to employ a guard-member which is normally out of operative position, so as to afford unobstructed access to the dies or other instrumentalities of the machine, but which is so connected with the mechanism by which the machine is started and stopped as to be moved into operative position just before, or at the same time that, the machine is thrown into operation by means of a treadle or other manually-operable member.

The present invention relates to guards of this type, and the object of the invention is to produce a guard of simple construction and reliable operation, and particularly to so arrange the mechanism by which the guard is actuated and the machine is controlled that the guard may be moved fully to operative position before any movement is imparted to the clutch or other device by which the machine is thrown into operation, thus avoiding the danger of operative movement of the machine before the guard has been brought into a position in which it will absolutely prevent the operator's hands from being engaged by the moving parts of the machine.

To the foregoing end the invention consists in the guard hereinafter described, as it is defined in the succeeding claims.

In the accompanying drawings: Figure 1 is a side-elevation of a press provided with a guard constructed in accordance with the present invention; Fig. 2 is a rear-elevation, on a larger scale, of a portion of the guard-mechanism including the three rocking-members; Fig. 3 is a vertical median section of the parts shown in Fig. 2; and Figs. 4, 5 and 6 are side-elevations, partially in

section, on the line X—X in Fig. 3, showing different operative positions of the guard-mechanism.

The invention is illustrated as applied to a press of ordinary form, such as is employed in metal-punching and stamping operations, this press having the usual vertically-movable head 1 and actuating-mechanism therefor including a drive-shaft 2. This drive-shaft is thrown into and out of operation in the usual manner, by a clutch which may be of any ordinary or suitable form, and is not, therefore, illustrated. This clutch is thrown into and out of operation in the usual manner, by means of mechanism including a bell-crank lever 3 pivoted on the frame 7 of the machine, this lever being rocked clockwise, or to the right, from the illustrated position in order to throw the clutch into operation. The press is also provided in the usual manner with a manually-operable member, in the form of a treadle 4, which is depressed by the operator for the purpose of throwing the driving-mechanism into operation. This treadle is carried by a lever 5, which is pivoted to the frame at 6 and is held normally in raised position by a spring 38. The guard-proper comprises a horizontal bar 8 which extends transversely in front of the head 1. This bar is mounted in a lug 9 adjustably fixed upon a lever 10, which extends rearwardly and is arranged to swing about a horizontal stud 11 projecting from the frame 7. When the machine is at rest the guard-bar 8 is held in raised position, the lever 10 being provided with a counterweight 12 for this purpose and being arrested in normal position by a stop-screw 13 threaded into a lug projecting from the frame 7.

In order to guard the hand of the operator from accidental engagement with the dies when the press is in operation it is necessary that the lever 10 be swung downwardly and the guard-bar 8 brought to the level of the table 26 of the press before the clutch is operated to start the movement of the press, and for this purpose the guard-mechanism is associated with the connections between the treadle-lever 5 and the bell-crank lever 3 through which the clutch is actuated. The construction by which this is accomplished is shown particularly in Figs. 2-6. The lever 10 is fixed in an arm constituting a

part of a rocking-member 14 journaled upon the stud 11. The rocking-member 14 is provided with a cylindrical hub or sleeve 15 which constitutes a journal and support for another rocking-member 16. The member 16 is also provided with an arm, to which is pivoted the upper end of a rod 17 connected, at its lower end, with the treadle-lever 5, so that when the treadle is depressed the member 16 is rocked about the sleeve 15. A washer 18 on the stud holds the members 14 and 16 against endwise movement therefrom. Still another rocking-member 19 is journaled on the stud, and has an arm which is connected, by a rod 20, with the bell-crank lever 3.

Since the rocking-member 16, through its connection with the treadle, constitutes means by which both the guard-proper and the clutch are actuated, and since it is desirable that the guard be brought fully into operative position before any movement is imparted to the clutch, it is necessary that after the guard has been so brought down the member 16 may be further actuated, by continued movement of the treadle, to operate the clutch, while the guard remains in stationary position. Accordingly, yielding connections are employed between the guard and the rocking-member 16, to permit independent movement of the latter. A post 21 projecting from the member 16, and a pin 22 projecting from the guard-lever 10, are connected by a tension-spring 23. In the normal position of the parts this spring is contracted, and it holds the rocking-members 14 and 16 in a relative position in which a lug 24 on the member 16 is engaged by a lug 25 on the member 14. When the treadle is depressed, thus causing the member 16 to rock to the left, the spring 23 causes the member 14 and the guard to swing downwardly, the lugs 24 and 25 remaining in engagement with each other until the guard-bar 8 rests upon the top of the table 26, as shown in Fig. 5. During this time the rocking-member 19 remains stationary, no movement being imparted to the clutch. In order that the clutch may be thrown into operation at the proper time, however, a lug 27 projects from the rocking-member 19 in a position in which it may be engaged by the inner extremity of the lug 24 when the member 16 has moved from the normal position of Fig. 4 to the position of Fig. 5. Accordingly, after the guard has been depressed as just described the continued downward movement of the treadle, through the engagement of the lugs 24 and 27, causes the member 19 to rock, thus pulling downwardly the rod 20 and swinging the bell-crank lever 3 so as to actuate the clutch and throw the driving-mechanism into operation. During this later part of the movement of the treadle the guard-proper and the member

14 remain stationary, and the spring 23 yields to permit the continued movement of the member 16.

It is important that in case the operator's hand be in position to be engaged by the guard in its descent the operation of the clutch be positively prevented until the hand has been withdrawn from such position. Accordingly, means are provided for positively interconnecting the members 16 and 14 under such circumstances, to interrupt the movement of the member 16 until the guard has been permitted to descend fully to operative position. For this purpose the member 14 is provided with a lug 28 having an adjustable stop-screw 29 which is adapted to engage the upper surface of the lug 24. The stop-screw is so adjusted that in the normal operation of the mechanism, when the guard has descended fully to operative position, the screw is not engaged by the lug 24 until the member 16 has been rocked throughout its entire range of movement and the clutch has been thrown into operation. As shown in Fig. 5, for example, it will be apparent that when the guard is in depressed position there is sufficient space between the screw 29 and the lug 24 to permit further movement of the member 16, and, as the lugs 24 and 27 are at this time in engagement, the member 19 will accordingly be rocked and the clutch thrown into operation. In case the downward movement of the guard be arrested, however, as shown, for example, in Fig. 6, by engagement with the hand of the operator, the lug 24 will engage the screw 29 either before the lug 27 has been engaged at all, or in any case before the lug 27 and the member 19 have been moved far enough to throw the clutch into operation. The member 16 being thus arrested positively, the machine cannot be started until the operator's hand has been withdrawn so as to permit the guard to descend fully.

In order that the operator may be prevented from introducing his hand to a position of danger after the guard has descended, a screen or plate 30 is preferably fixed to the bar 8 so as to project upwardly therefrom and close the entire space between the table 26 and the head 1 of the press. The arrangement of the rocking-members 14 and 16 by which the latter is journaled upon the former, as described, not only renders the mechanism compact and rigid, but also reduces the friction of its operation, since the members 14 and 16 turn as one during the first part of their operative movements.

A valuable feature of the present invention resides in the fact that in the normal operation of the device the guard is brought fully to its operative position before any movement is imparted to the clutch to throw the driving-mechanism into op-

eration. In guards previously employed this has not been the case, but movement has been imparted simultaneously to the clutch and to the guard during the whole or a portion of the operative movement of the guard. Such an arrangement is, however, unreliable owing to the fact that the guard does not fully reach its operative position before movement is imparted to the clutch, so that as the result of wear upon the parts of the clutch-mechanism the clutch is liable to become operative before the full movement of the controlling-mechanism originally provided for, and, accordingly, guards constructed as just described do not constitute complete safeguards against the presence of the operator's hand at the point of danger when the machine begins to operate.

20 My invention is not limited to the embodiment thereof hereinbefore described and illustrated in the accompanying drawings, but may be embodied in various other forms within the nature of the invention as it is defined in the following claims.

I claim:—

1. In combination with a press having a driving-clutch and a treadle; a first rocking-member having a bearing on a fixed part of the machine and connected with the treadle; a second rocking-member journaled coaxially with the first and connected with the clutch; a third rocking-member journaled coaxially with the first and second and carrying a guard adapted to swing into position in front of the operative instrumentalities of the press; a spring connecting the first and third rocking-members to swing the guard into operative position during the first part of the movement of the treadle; coöperating abutments on the first and third rocking-members, normally separated to provide lost-motion, but adapted to move the second rocking-member and throw the clutch into operation during the later part of the movement of the treadle; means for raising the guard out of operative position when the treadle is in normal position and the clutch disengaged; and a stud fixed in the frame and upon which the second and third rocking-members are mounted directly, the first rocking-member being mounted, and having a bearing, upon the third rocking-member concentric with the stud.

first and second rocking-members normally separated to provide lost-motion but adapted to move the second rocking-member and throw the clutch into operation during the later part of the movement of the treadle; and means for raising the guard out of operative position when the treadle is in normal position and the clutch disengaged.

2. In combination with a press having a driving-clutch and a treadle; a first rocking-member having a bearing on a fixed part of the machine and connected with the treadle; a second rocking-member journaled coaxially with the first and connected with the clutch; a third rocking-member journaled coaxially with the first and second and carrying a guard adapted to swing into position in front of the operative instrumentalities of the press; a spring connecting the first and third rocking-members to swing the guard into operative position during the first part of the movement of the treadle; coöperating abutments on the first and third rocking-members, normally separated to provide lost-motion, but adapted to move the guard positively to operative position during the later part of the movement of the treadle; coöperating abutments on the first and second rocking-members, normally separated to provide lost-motion, but adapted to move the second rocking-member and throw the clutch into operation during the later part of the movement of the treadle; means for raising the guard out of operative position when the treadle is in normal position and the clutch disengaged; and a stud fixed in the frame and upon which the second and third rocking-members are mounted directly, the first rocking-member being mounted, and having a bearing, upon the third rocking-member concentric with the stud.
